UNITED STATES PATENT OFFICE.

JAMES IRA PITTMAN, OF LONGWOOD, FLORIDA.

TURPENTINE-DISTILLING APPARATUS.

SPECIFICATION forming part of Letters Patent No. 742,351, dated October 27, 1903.

Application filed September 16, 1902. Serial No. 128,608. (No model.)

To all whom it may concern:

Be it known that I, JAMES IRA PITTMAN, a citizen of the United States, residing at Longwood, in the county of Orange and State of Florida, have invented new and useful Improvements in Turpentine-Distilling Apparatus, of which the following is a specification.

This invention relates to a turpentine-distilling apparatus; and the object of the invention is to provide an effective apparatus of this character which is adapted to quickly and thoroughly distil the crude material, the latter being supplied in proper quantity to the still wholly free from dirt, sticks, sand, and other foreign substances.

In the present case the apparatus is mounted upon a vehicle or carriage of some suitable kind, so that it can be readily moved from place to place by horse or other power, or, if desired, the working parts of the apparatus may be taken from the vehicle or carriage and placed upon the ground for use.

The improved apparatus includes in its construction a still and primary and secondary vats, the crude material containing the chips, dirt, &c., being placed in the primary vat, where it is heated, and thereby caused to liquefy and flow into the secondary vat. The discharge end of the primary vat has a perforated or netted portion or wall through which the semifluid crude material is adapted to flow and which strains the same, so that such material enters the secondary vat entirely free of all objectionable matter. The secondary vat delivers the substance by means of a trough or other similar agent into the still, and when said still receives a sufficient quantity of the said substance a cap is placed upon the same and heat applied thereto in order to distil such substance. Upon the application of heat to the still the vapors pass into a condensing coil or worm in communication with the still and which coil or worm is disposed in a vessel or receptacle adapted to contain a cooling medium, such as water, such cooling medium facilitating the condensation of the vapors. A pipe extends from the vessel or receptacle, and its delivery end is situated in proximity to the point where the still is charged with the crude material in order to supply said still with water for a purpose that will hereinafter appear.

The invention is clearly illustrated in the accompanying drawings, forming a part of this specification, in which—

Figure 1 is a sectional side elevation of a distilling apparatus embodying said invention. Fig. 2 is a sectional detail view.

Like characters refer to like parts in both figures.

The different parts of the apparatus are mounted upon a vehicle, as 2, which may be of any suitable character and which can be moved from place to place, as required, by horse or other power, or, if desired, the still and its coöperative parts may be dismounted from the vehicle and placed upon the ground for use and used as a stationary apparatus.

The still is denoted by 3, and it is practically wholly incased by the jacket 4, closed upon its upper side, and into the space between the jacket and the still steam is admitted in order to heat the contents of the still for the purpose of distilling the same. A pipe 5 depends from the bottom of the still and it is valved, the pipe serving as a means to draw off the resin or non-distilled portion of the charge. A valved pipe, as 6, leads from the steam-jacket, the function of the same being to carry off the water of condensation from the space between the still and jacket.

A boiler, as 7, is mounted upon the vehicle and is connected by the steam-supply pipe 8 with the steam-jacket 4, said pipe serving to feed steam into the space between the jacket and still, so as to distil the contents of the latter, the pipe, of course, being provided with a valve for controlling the flow of such steam. This valve while the still is being charged with the crude material is closed. As soon as the charge has been delivered to the still and the same is covered steam will be admitted into the steam-space mentioned, for the purpose set forth.

The upper open side or mouth of the still is closed by the enlarged terminal end of the conduit 9, which enlarged terminal end constitutes a cap for the still. The opposite end of the conduit 9 is united to the condensing coil or worm 10, supported within the vessel or receptacle 11, suitably mounted and adapted to contain water or other cooling medium, water being preferably employed, although I do not show any means for supplying the

same to the vessel, for it may be poured therein, if desired. The lower terminal coil of the worm extends through the bottom of the vessel 11 and is provided with a plug or valve of some suitable kind, by opening which the distilled vapors can be drawn off in the form of turpentine into suitable vessels. It will be understood that the enlarged inner terminal end of the conduit 9 constitutes a cap for and is, in fact, a part of the still 3, said enlarged end or cap being removable for the purpose of charging the still or the body portion thereof with the crude material.

15 I show primary and secondary vats 12 and 13 suitably mounted upon the framing, the primary vat 12 being located in a plane above the secondary vat 13, so that the crude gum can flow from the former into the latter, the secondary vat being put into communication by means of a trough, as 14, with the mouth of the still 3. Pipes, as 15, extend lengthwise of the vats and are connected by the valved supply-pipe 16 with the boiler 7. The vats, like the other parts of the apparatus, may be made of any suitable material, and the discharge-wall of the primary vat 12 is made of perforated material or netting. A supply of material having been emptied into the primary vat 12, steam will be admitted to the pipes 15 in the vats by opening the valve in the supply-pipe 16, so as to partially liquefy the material in the primary vat, and when the same is in a sufficiently fluid condition it flows 25 from the primary vat into the secondary vat, the foreign matter in the material being strained from the material by means of the perforated wall just mentioned. The cap of the still 3 having been taken off and the 30 trough having been put into position with its discharge end over the mouth of said still the gate 17 of the said trough will be lifted, so as to permit the fluid material to pass from the secondary vat into the trough and from the 35 latter into the still, the operation being repeated until the level of the material in the still has reached a desired line. When this is done, the steam flowing through the supply-pipe will be cut off and the still 3 will be covered.

40 Before distilling the gum in the still I feed to the latter a supply of water which is thoroughly mixed with the gum while in the still in order that such gum can be properly cooked, the steam which rises from the cooking mass passing into the enlarged inner terminal end of the "gooseneck" conduit 9 and thence to the condensing-coil 10, where it is condensed, as hereinbefore set forth. To provide the 45 still with the water, I extend the pipe 18 from the tank 11 to said terminal end of the conduit, the inlet end of the pipe being situated near the top of the tank. Said pipe is provided with a valve to regulate the flow of water to the still. The cap of the still 3 having been put on and the gate 17 of the trough 14 having been closed and the valve of the pipe

50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

16 having been also closed, steam will be admitted into the space between the still and jacket 4 by means of the pipe 8, the valve of the latter having been opened for this purpose, so as to distil the contents of the still, the vapor passing from the still into the conduit 9 and from the latter into the worm or coil 10, where it is condensed and drawn off from the terminal coil of the worm, as is the custom in this art.

17 The steam-jacket is provided with a steam-pressure gage 19 of some suitable kind, serving its usual function.

18 The primary and secondary vats 12 and 13, in connection with the cooling-medium-containing receptacle or vessel 11 and their co-operating parts, can be employed in conjunction with various kinds of stills. By virtue of my improvements it will be seen that the crude material is placed in the still in a condition absolutely free of all foreign or objectionable matter and that the clogging of the material at the mouth of the still is positively prevented. The apparatus is simple and effective in operation, and it can be constructed at a reasonable figure, and may be readily transported from place to place, or the operating parts can be taken from the carriage or vehicle, if desired.

19 A block and tackle 20 is provided to hoist the barrels containing the crude gum to the primary vat 12, and after the barrels have

20 been emptied they can be steamed by inverting them over the said primary vat.

21 The non-distilled matter from the draw-off pipe 5 is adapted to flow into the tank 21, from

22 which it can be intermittently discharged by means of the gate-regulated spout 22.

23 The non-distilled matter from the draw-off pipe 5 is adapted to flow into the tank 21, from

24 which it can be intermittently discharged by means of the gate-regulated spout 22.

25 The non-distilled matter from the draw-off pipe 5 is adapted to flow into the tank 21, from

26 which it can be intermittently discharged by means of the gate-regulated spout 22.

27 The non-distilled matter from the draw-off pipe 5 is adapted to flow into the tank 21, from

28 which it can be intermittently discharged by means of the gate-regulated spout 22.

29 The non-distilled matter from the draw-off pipe 5 is adapted to flow into the tank 21, from

30 which it can be intermittently discharged by means of the gate-regulated spout 22.

31 The non-distilled matter from the draw-off pipe 5 is adapted to flow into the tank 21, from

32 which it can be intermittently discharged by means of the gate-regulated spout 22.

33 The non-distilled matter from the draw-off pipe 5 is adapted to flow into the tank 21, from

34 which it can be intermittently discharged by means of the gate-regulated spout 22.

35 The non-distilled matter from the draw-off pipe 5 is adapted to flow into the tank 21, from

36 which it can be intermittently discharged by means of the gate-regulated spout 22.

37 The non-distilled matter from the draw-off pipe 5 is adapted to flow into the tank 21, from

38 which it can be intermittently discharged by means of the gate-regulated spout 22.

39 The non-distilled matter from the draw-off pipe 5 is adapted to flow into the tank 21, from

40 which it can be intermittently discharged by means of the gate-regulated spout 22.

41 The non-distilled matter from the draw-off pipe 5 is adapted to flow into the tank 21, from

42 which it can be intermittently discharged by means of the gate-regulated spout 22.

43 The non-distilled matter from the draw-off pipe 5 is adapted to flow into the tank 21, from

44 which it can be intermittently discharged by means of the gate-regulated spout 22.

45 The non-distilled matter from the draw-off pipe 5 is adapted to flow into the tank 21, from

46 which it can be intermittently discharged by means of the gate-regulated spout 22.

47 The non-distilled matter from the draw-off pipe 5 is adapted to flow into the tank 21, from

48 which it can be intermittently discharged by means of the gate-regulated spout 22.

49 The non-distilled matter from the draw-off pipe 5 is adapted to flow into the tank 21, from

50 which it can be intermittently discharged by means of the gate-regulated spout 22.

51 The non-distilled matter from the draw-off pipe 5 is adapted to flow into the tank 21, from

52 which it can be intermittently discharged by means of the gate-regulated spout 22.

53 The non-distilled matter from the draw-off pipe 5 is adapted to flow into the tank 21, from

54 which it can be intermittently discharged by means of the gate-regulated spout 22.

55 The non-distilled matter from the draw-off pipe 5 is adapted to flow into the tank 21, from

56 which it can be intermittently discharged by means of the gate-regulated spout 22.

57 The non-distilled matter from the draw-off pipe 5 is adapted to flow into the tank 21, from

58 which it can be intermittently discharged by means of the gate-regulated spout 22.

59 The non-distilled matter from the draw-off pipe 5 is adapted to flow into the tank 21, from

60 which it can be intermittently discharged by means of the gate-regulated spout 22.

61 The non-distilled matter from the draw-off pipe 5 is adapted to flow into the tank 21, from

62 which it can be intermittently discharged by means of the gate-regulated spout 22.

63 The non-distilled matter from the draw-off pipe 5 is adapted to flow into the tank 21, from

64 which it can be intermittently discharged by means of the gate-regulated spout 22.

65 The non-distilled matter from the draw-off pipe 5 is adapted to flow into the tank 21, from

66 which it can be intermittently discharged by means of the gate-regulated spout 22.

67 The non-distilled matter from the draw-off pipe 5 is adapted to flow into the tank 21, from

68 which it can be intermittently discharged by means of the gate-regulated spout 22.

69 The non-distilled matter from the draw-off pipe 5 is adapted to flow into the tank 21, from

70 which it can be intermittently discharged by means of the gate-regulated spout 22.

71 The non-distilled matter from the draw-off pipe 5 is adapted to flow into the tank 21, from

72 which it can be intermittently discharged by means of the gate-regulated spout 22.

73 The non-distilled matter from the draw-off pipe 5 is adapted to flow into the tank 21, from

74 which it can be intermittently discharged by means of the gate-regulated spout 22.

75 The non-distilled matter from the draw-off pipe 5 is adapted to flow into the tank 21, from

76 which it can be intermittently discharged by means of the gate-regulated spout 22.

77 The non-distilled matter from the draw-off pipe 5 is adapted to flow into the tank 21, from

78 which it can be intermittently discharged by means of the gate-regulated spout 22.

79 The non-distilled matter from the draw-off pipe 5 is adapted to flow into the tank 21, from

80 which it can be intermittently discharged by means of the gate-regulated spout 22.

81 The non-distilled matter from the draw-off pipe 5 is adapted to flow into the tank 21, from

82 which it can be intermittently discharged by means of the gate-regulated spout 22.

83 The non-distilled matter from the draw-off pipe 5 is adapted to flow into the tank 21, from

84 which it can be intermittently discharged by means of the gate-regulated spout 22.

85 The non-distilled matter from the draw-off pipe 5 is adapted to flow into the tank 21, from

86 which it can be intermittently discharged by means of the gate-regulated spout 22.

87 The non-distilled matter from the draw-off pipe 5 is adapted to flow into the tank 21, from

88 which it can be intermittently discharged by means of the gate-regulated spout 22.

89 The non-distilled matter from the draw-off pipe 5 is adapted to flow into the tank 21, from

90 which it can be intermittently discharged by means of the gate-regulated spout 22.

91 The non-distilled matter from the draw-off pipe 5 is adapted to flow into the tank 21, from

92 which it can be intermittently discharged by means of the gate-regulated spout 22.

93 The non-distilled matter from the draw-off pipe 5 is adapted to flow into the tank 21, from

94 which it can be intermittently discharged by means of the gate-regulated spout 22.

95 The non-distilled matter from the draw-off pipe 5 is adapted to flow into the tank 21, from

96 which it can be intermittently discharged by means of the gate-regulated spout 22.

97 The non-distilled matter from the draw-off pipe 5 is adapted to flow into the tank 21, from

98 which it can be intermittently discharged by means of the gate-regulated spout 22.

99 The non-distilled matter from the draw-off pipe 5 is adapted to flow into the tank 21, from

100 which it can be intermittently discharged by means of the gate-regulated spout 22.

101 The non-distilled matter from the draw-off pipe 5 is adapted to flow into the tank 21, from

102 which it can be intermittently discharged by means of the gate-regulated spout 22.

103 The non-distilled matter from the draw-off pipe 5 is adapted to flow into the tank 21, from

104 which it can be intermittently discharged by means of the gate-regulated spout 22.

105 The non-distilled matter from the draw-off pipe 5 is adapted to flow into the tank 21, from

106 which it can be intermittently discharged by means of the gate-regulated spout 22.

107 The non-distilled matter from the draw-off pipe 5 is adapted to flow into the tank 21, from

108 which it can be intermittently discharged by means of the gate-regulated spout 22.

109 The non-distilled matter from the draw-off pipe 5 is adapted to flow into the tank 21, from

110 which it can be intermittently discharged by means of the gate-regulated spout 22.

111 The non-distilled matter from the draw-off pipe 5 is adapted to flow into the tank 21, from

112 which it can be intermittently discharged by means of the gate-regulated spout 22.

113 The non-distilled matter from the draw-off pipe 5 is adapted to flow into the tank 21, from

114 which it can be intermittently discharged by means of the gate-regulated spout 22.

115 The non-distilled matter from the draw-off pipe 5 is adapted to flow into the tank 21, from

116 which it can be intermittently discharged by means of the gate-regulated spout 22.

117 The non-distilled matter from the draw-off pipe 5 is adapted to flow into the tank 21, from

118 which it can be intermittently discharged by means of the gate-regulated spout 22.

119 The non-distilled matter from the draw-off pipe 5 is adapted to flow into the tank 21, from

120 which it can be intermittently discharged by means of the gate-regulated spout 22.

121 The non-distilled matter from the draw-off pipe 5 is adapted to flow into the tank 21, from

122 which it can be intermittently discharged by means of the gate-regulated spout 22.

123 The non-distilled matter from the draw-off pipe 5 is adapted to flow into the tank 21, from

124 which it can be intermittently discharged by means of the gate-regulated spout 22.

125 The non-distilled matter from the draw-off pipe 5 is adapted to flow into the tank 21, from

126 which it can be intermittently discharged by means of the gate-regulated spout 22.

127 The non-distilled matter from the draw-off pipe 5 is adapted to flow into the tank 21, from

128 which it can be intermittently discharged by means of the gate-regulated spout 22.

129 The non-distilled matter from the draw-off pipe 5 is adapted to flow into the tank 21, from

130 which it can be intermittently discharged by means of the gate-regulated spout 22.

131 The non-distilled matter from the draw-off pipe 5 is adapted to flow into the tank 21, from

132 which it can be intermittently discharged by means of the gate-regulated spout 22.

133 The non-distilled matter from the draw-off pipe 5 is adapted to flow into the tank 21, from

134 which it can be intermittently discharged by means of the gate-regulated spout 22.

135 The non-distilled matter from the draw-off pipe 5 is adapted to flow into the tank 21, from

136 which it can be intermittently discharged by means of the gate-regulated spout 22.

137 The non-distilled matter from the draw-off pipe 5 is adapted to flow into the tank 21, from

138 which it can be intermittently discharged by means of the gate-regulated spout 22.

139 The non-distilled matter from the draw-off pipe 5 is adapted to flow into the tank 21, from

140 which it can be intermittently discharged by means of the gate-regulated spout 22.

141 The non-distilled matter from the draw-off pipe 5 is adapted to flow into the tank 21, from

142 which it can be intermittently discharged by means of the gate-regulated spout 22.

143 The non-distilled matter from the draw-off pipe 5 is adapted to flow into the tank 21, from

144 which it can be intermittently discharged by means of the gate-regulated spout 22.

145 The non-distilled matter from the draw-off pipe 5 is adapted to flow into the tank 21, from

146 which it can be intermittently discharged by means of the gate-regulated spout 22.

147 The non-distilled matter from the draw-off pipe 5 is adapted to flow into the tank 21, from

148 which it can be intermittently discharged by means of the gate-regulated spout 22.

149 The non-distilled matter from the draw-off pipe 5 is adapted to flow into the tank 21, from

150 which it can be intermittently discharged by means of the gate-regulated spout 22.

151 The non-distilled matter from the draw-off pipe 5 is adapted to flow into the tank 21, from

152 which it can be intermittently discharged by means of the gate-regulated spout 22.

153 The non-distilled matter from the draw-off pipe 5 is adapted to flow into the tank 21, from

154 which it can be intermittently discharged by means of the gate-regulated spout 22.

155 The non-distilled matter from the draw-off pipe 5 is adapted to flow into the tank 21, from

156 which it can be intermittently discharged by means of the gate-regulated spout 22.

157 The non-distilled matter from the draw-off pipe 5 is adapted to flow into the tank 21, from

158 which it can be intermittently discharged by means of the gate-regulated spout 22.

159 The non-distilled matter from the draw-off pipe 5 is adapted to flow into the tank 21, from

160 which it can be intermittently discharged by means of the gate-regulated spout 22.

161 The non-distilled matter from the draw-off pipe 5 is adapted to flow into the tank 21, from

162 which it can be intermittently discharged by means of the gate-regulated spout 22.

163 The non-distilled matter from the draw-off pipe 5 is adapted to flow into the tank 21, from

164 which it can be intermittently discharged by means of the gate-regulated spout 22.

165 The non-distilled matter from the draw-off pipe 5 is adapted to flow into the tank 21, from

166 which it can be intermittently discharged by means of the gate-regulated spout 22.

167 The non-distilled matter from the draw-off pipe 5 is adapted to flow into the tank 21, from

168 which it can be intermittently discharged by means of the gate-regulated spout 22.

169 The non-distilled matter from the draw-off pipe 5 is adapted to flow into the tank 21, from

170 which it can be intermittently discharged by means of the gate-regulated spout 22.

171 The non-distilled matter from the draw-off pipe 5 is adapted to flow into the tank 21, from

172 which it can be intermittently discharged by means of the gate-regulated spout 22.

173 The non-distilled matter from the draw-off pipe 5 is adapted to flow into the tank 21, from

174 which it can be intermittently discharged by means of the gate-regulated spout 22.

175 The non-distilled matter from the draw-off pipe 5 is adapted to flow into the tank 21, from

176 which it can be intermittently discharged by means of the gate-regulated spout 22.

177 The non-distilled matter from the draw-off pipe 5 is adapted to flow into the tank 21, from
